Patented July 26, 1921.

FIG. 1

FIG. 2

A

FIG. 3

Inventor,
Hermann Egloff,

By *Raymond J. Blakeslee*,

His Attorney.

UNITED STATES PATENT OFFICE.

HERMANN EGLOFF, OF LOS ANGELES, CALIFORNIA.

VALVE-LIFTING DEVICE.

1,385,436.

Specification of Letters Patent. Patented July 26, 1921.

Application filed September 4, 1919. Serial No. 321,698.

To all whom it may concern:

Be it known that I, HERMANN EGLOFF, a citizen of Switzerland, residing at 2224 Ocean View Ave., Los Angeles, in the county 5 of Los Angeles and State of California, have invented a new and useful Valve-Lifting Device, of which the following is a specification.

This invention relates to a valve lifting 10 device, and has for an object the provision of means whereby upon movement of the valve lifter a certain distance, the valve head will be moved a proportionately greater distance. Advantage is taken of 15 the fact that a short movement of any fulcrum lever will transmit a greater distance to the longest arm thereof.

In practicing this invention I provide means placed intermediate an end of the 20 valve stem and an end of the valve lifter, which means consists of lever arms arranged crosswise held and pivoted in an independent frame member; a detached rectangular cap placed on the end of the tappet or valve 25 lifter or plunger in order that the downward intermediate projections of the levers will not have any overhang; and a detached grooved counterbored rectangular plate, on the slotted or grooved portion of which the 30 ends of the levers opposite their pivot points operate, and on which the end of the valve stem opposite the valved seats in the counterbore.

The invention has for an object the 35 provision of an improved valve lifting device which will allow a greater valve lift than hitherto, and which will be superior in point of relative simplicity and inexpensiveness, taken in conjunction with utility, durability, 40 general efficiency and serviceability.

With the above and other objects in view, the invention consists in the novel arrangement of parts utilized for lifting the valve, and in the formation, construction, combination, 45 association and inter-relation of the different members, all as disclosed in the accompanying drawing, described in the following statement, and finally pointed out in claims.

In the drawing:

Figure 1 illustrates a fragmentary elevation of a "valve on the side" type utilizing the improved valve lifting device;

Fig. 2 is a fragmentary elevation similar 55 to Fig. 1, but showing the valve lifting device in operation with the valve head un-

seated, the cam member having rotated 180 degrees from the showing in Fig. 1;

Fig. 3 is a fragmentary elevation showing 60 a side view of Fig. 2.

Corresponding parts in all the figures are designated by the same reference characters.

Referring with particularity to the drawing, I have shown in the various figures certain standard parts which are now utilized 65 in internal combustion engines for admitting a power giving fluid to the combustion chamber, or for allowing gas to escape from the combustion chamber of an engine.

In the drawing, A designates the valve of 70 which 1 is a valve stem and 2 a valve lifter or plunger or tappet. As before mentioned the drawing shows a "valve on the side" type, but I do not wish to be understood as 75 confining my invention to a valve of this type, inasmuch as the "valve in the head" type might as readily be utilized in my invention.

The valve stem is provided with a valve 80 spring seat or washer 3 which seat is keyed as at 4, or otherwise held, to a portion of the valve stem 1. A valve cage 5 has a valve stem guide 6 through which the valve stem extends. A top portion of the valve cage 5 is provided with a valve seat 7, shown in 85 dotted lines. Surrounding a portion of the valve stem guide 6 and coacting with a portion of the valve cage 5 as at 8 and with the valve seat 3, as at 9, is a helical spring 10. It is ordinary practice in any valve to include a 90 spring 10, as above described, and the spring is used to close a valve head 11 upon the valve seat 7 during certain rotation of the cam, to be described later.

Opposite the valve head 11 is a transverse 95 rectangular member 13. This member is provided with a counterbore 14 in which the end of the valve stem opposite the valve head seats. This member is provided with a longitudinal grooved portion 15.

The valve lifter or plunger or tappet 2 passes through a guide bushing 16. One end of the valve lifter 2 is provided with a disk 17 which co-operates with a cam member 18 rotating upon its shaft 19.

In this invention a means is provided between an end 20 of the valve lifter 2 and the end 12, which means serves to transmit a proportionately greater upward movement to the valve than the movement of the valve lifter. The means comprises cross lever arms 22 and 23 so formed that one end of

same is angularly directed and provided with boss portions 24 and 25. Means such as pins 26 and 27 pass through the perforations in the boss portions 24 and 25 and 5 engage with a frame member α .

The frame member is independent of the engine casing. The arms 22 and 23 are identical in formation, and a part as 28 on each of the arms is downwardly directed. The 10 downwardly directed portion 28 really constitutes a projection formed intermediate an edge portion of the arms 22 and 23. The portion 28 is so arranged that it engages the end 20 of the valve lifter 2 as shown at 21. 15 End portions 29 and 30 of the lever arms 22 and 23 slide within the groove 15 of the member 13.

It will thus be seen that the groove 15 acts as a guide for the ends 29 and 30 of each 20 of the lever arms. As will be observed by referring to the figures the lever arms 22 and 23 are so joined to the frame member α that the pivoted portions, or rather the boss portions, straddle the end as at 21 of 25 the valve lifter 2.

It is obvious that the frame member might be dispensed with, and bracket members secured to the guide bushing 16, which 30 members would support the levers 22 and 23. This would simply be a matter of choice. In the ordinary gas engine, the valve stem will be lifted so that the valve head will be unseated a distance dependent upon the size of the cam member 18, minus 35 of course the valve clearance, when the cam has rotated so as to lift the valve plunger its maximum upward distance.

With this device I take advantage of the relative movement of the pivoted levers 22 40 and 23, and as the pivot levers are identically formed, a slight movement of the lever arms 22 and 23 at some portion intermediate thereof, will lift the end portions as 29 and 30 a proportionately greater distance 45 dependent upon the distance between the point of contact of the projections 28 on each of the lever arms and the ends 29 and 30.

The lever arms as arranged will act upon the member 13 so that any impulse or movement 50 of the valve lifter 2 will be transmitted equally through the lever arms to the valve stem 1.

It is obvious that many minor changes and variations and modifications may be 55 made in departure from the particular description and showing of the accompanying drawing, in adapting the invention to varying conditions and requirements of use and service, without departing from the true 60 spirit of the invention.

Having thus disclosed my invention, I claim and desire to secure by Letters Patent.

1. A valve lifting device, the combination with a valve and valve lifter, of means whereby upon movement of the valve lifter the valve is raised to a degree in excess of the rise of the valve lifter; said means comprising crossed levers. 65

2. In a valve lifting device, the combination with a valve and valve lifter, of means whereby upon movement of the valve lifter, the valve stem is raised to a degree in excess of the rise of the valve lifter; said means comprising crossed levers, and said levers 70 being provided with bossed portions pivotally mounted at opposite sides of said valve lifter, and the said levers likewise having projections engaged by the valve lifter in sliding contact. 75

3. In a valve lifting device, the combination with a valve and valve lifter, of means whereby upon movement of the valve lifter, the valve stem is raised to a degree in excess of the rise of the valve lifter; said 80 means comprising crossed levers, and said levers being provided with bossed portions pivotally mounted at opposite sides of said valve lifter; and a transverse member placed in position intermediate an end of 85 the valve stem and ends of the crossed levers opposite the pivoted bossed portions. 90

4. In a valve lifting device, the combination with a valve and valve lifter, of means whereby upon movement of the valve lifter, the valve stem is raised to a degree in excess of the rise of the valve lifter; said 95 means comprising crossed levers, and said levers being provided with bossed portions pivotally mounted at opposite sides of said valve lifter, and a transverse member placed in position intermediate an end of the valve stem and ends of the crossed levers opposite the pivoted bossed portions; said transverse member being provided with a longitudinal 100 groove within which play the ends of said levers. 105

5. In a valve lifting device, the combination with a valve and valve lifter, of means whereby upon movement of the valve lifter, the valve stem is raised to a degree in excess of the rise of the valve lifter; said 110 means comprising crossed levers, and said levers being provided with bossed portions pivotally mounted at opposite sides of said valve lifter, and a transverse member placed in position intermediate an end of the valve stem and ends of the crossed levers opposite the pivoted bossed portions; said transverse member being provided with a longitudinal 115 groove within which play the ends of said levers; said transverse member likewise being formed with a counterbore within which seats the end of valve stem 120 which is opposite its valve head.

HERMANN EGLOFF.
